UNITED STATES PATENT OFFICE.

JOHN GRAVES, OF MADISON, WISCONSIN, ASSIGNOR TO FRENCH BATTERY & CARBON CO., OF MADISON, WISCONSIN, A CORPORATION OF WISCONSIN.

CORE-TAMPING MACHINE.

1,304,559.

Specification of Letters Patent. Patented May 27, 1919.

Application filed January 25, 1919. Serial No. 273,183.

To all whom it may concern:

Be it known that I, JOHN GRAVES, a citizen of the United States, residing at Madison, in the county of Dane and State of Wisconsin, have invented a certain new and useful Improvement in Core-Tamping Machines, of which the following is a specification.

This invention relates to core tamping machines, particularly those in which more than one tool is required in the tamping operation, or some operation in connection therewith. The object of the invention is to provide a machine of this class having a mold for the core, means for ejecting the product therefrom, and a single reciprocatable tool body carried in fixed guides, thereby insuring accuracy, said tool being, at the will of the operator, convertible first into one form of tool and then into another, but this without the use of the objectionable turret wheel, common in the art, carrying a multiplicity of tools. The invention consists in means for carrying out the foregoing objects, which is compact in construction, which can be easily and conveniently made, which is satisfactory in operation and is not readily liable to get out of order. More in detail, the invention consists in the features and details of construction which will be hereafter more fully set forth in the specification and claims.

Referring to the drawings, in which similar numerals represent the same parts throughout the several views,

Figure 1 is a vertical front view of mechanism illustrating this invention in its preferred form.

Fig. 2 is a side elevation taken at the right hand side of Fig. 1.

Fig. 3 is a central sectional view, taken on the line 3-3 of Fig. 1.

Fig. 4 is a changed position view of the tool member proper, showing the position of the parts with the carbon pencil ready to be inserted in the core.

Fig. 5 is another changed position view of Fig. 3, showing the tool mechanism in the act of finishing the insertion of the carbon pencil in the core.

Fig. 6 is a perspective view showing a bobbin or core of an electric dry battery, comprising a core proper of depolarizing material and a carbon pencil embedded therein which the particular machine herein shown

as embodying this invention was especially designed to make.

Fig. 7 is a changed position view of the resetting lever mechanism appearing in normal position in the upper portion of Fig. 1.

The mechanism embodying this invention is supported upon a suitable frame which, in the particular form here illustrated, comprises a table 10, an upright column 12, and a depending lug 14 supported from the floor or ground by mechanism forming no part of this invention, and therefore not shown. The column 12 is made U-shaped, as clearly appears in Fig. 1, to support parallel guides 16 and 18, which form a vertical trackway for a crosshead 20, supporting the working tool mechanism hereafter set forth. The particular means shown in the drawing for reciprocating this crosshead vertically comprises a rack 22 on the back of the crosshead with which meshes a segmental gear 24 carried by a shaft 26, journaled in the column 12, and driven selectively at the will of the operator by the use of either one of two handles 28 and 30 mounted for convenience on opposite ends of shaft 26.

Extending from the front of crosshead 20 is a horizontal lug 32 bored out vertically to form the hole 34 in whose lower end is inserted the shank 36 of tamping tool 38, detachably secured in position by any suitable means, as for instance set screw 40. This tamping tool 38 may, if desired, be provided with a detachable replaceable working end 38^a which is, in the particular case here illustrated, secured in place by screw-threads 42.

The tool 38-38^a, just referred to, is longitudinally bored to receive a reciprocatable carbon-inserting tool 44, whose upper end is attached by any suitable means, as for instance the screw-threads 46, to a second crosshead 48 which is reciprocatable in hole 34. Pivoted to crosshead 48 by a crank pin 50 is a connecting rod 52 whose upper end is pivotally connected by a crank pin 54 to a rotatable disk 56 journaled in a boss 58 on the face of crosshead 20. This disk 56 is detachably secured in rotatable position in the boss 58 by means of a set screw 60 (Fig. 3) whose end enters and takes bearing in an annular recess 62 cut in the circumferential face of disk 56. The upper end of connecting rod 52 enters and partially rotates within a slot 64 formed for its reception in substantially half of the disk 56. This slot is

licated and arranged so that partial rotation of the disk 56 will move the connecting rod 52 and attached parts from the full line position of Fig. 1 to the dotted line position of Fig. 7, and vice versa.

From the foregoing construction, it will be seen that in either one of the positions just referred to, rotation of shaft 26, and consequently reciprocation of crosshead 20, will vertically reciprocate the tool member 38 and attached parts. When connecting rod 52 is in the position shown in Fig. 1 and this reciprocation takes place, the carbon inserting tool 44 is in the position of Fig. 3, and when connecting rod 52 is in the position of Fig. 7 and this reciprocation takes place, carbon-inserting tool 44 is with reference to tool 38 in the position of Fig. 4.

Disk 56 is rotatable between the positions just described through the use of a lever 66 detachably secured to the disk by any suitable means, as for instance by screw 68. A projecting lug 70 on the disk 56 and a pin 72 on the boss 58 engageable by said lug 70 serves to limit the arc of travel of the disk and consequently the stroke of the tool 38 and attached parts heretofore described.

On guide 16 is a stop 74 adapted, when engaged by the end 66 of lever 66 while the parts are in the position shown in Fig. 7 and the crosshead 20 is moving upward, to, in the manner hereafter described, cause lever 66 and attached parts to return from the position of Fig. 7 to that of Fig. 1.

In a portion of the circumferential face of disk 56 which is within the boss 58 is a cam face 76 (Fig. 1). Adjacent to this cam face is a reciprocatable rod 78 whose head, shown in Fig. 1, is pressed by a spring 80 against this cam face 76. The outer end of the rod 78 is movable between two positions; that of Fig. 1 in which, as the crosshead 20 reciprocates vertically, it never touches stop 82 on guide 18, and that of Fig. 7, in which it is extended so as to engage said stop 82 and limit the downward movement of the tool 38 and attached parts. This mechanism just referred to is provided to prevent the carbon pencil being driven too far into the core.

On the table 10 is secured, by any suitable means, as for instance screw 84, a clamping device 86 adapted to detachably engage and hold a mold member 88, within which the core 90 is adapted to be first formed and thereafter receive the carbon pencil 92. The combination bottom and finished work-ejecting member of this mold is a reciprocatable plunger 94, whose lower end is detachably and adjustably secured to a horizontal crosshead 96 by a set screw 98, the crosshead being in turn slidably vertically on rods 100, projecting from the bottom of table 10, as shown in Fig. 1 and adjustably positioned so as to travel thereon by any suitable means, as for

instance the lock-nuts 102. The plunger 94 may, if desired, be provided with a detachable replaceable upper working end 94^a which is in the drawings shown applied through the agency of screw-threads 104.

Reciprocatable vertically through the table 10 and bracket 14 is a rod 110 whose upper end is attached by any suitable means, as for instance by the screw device 112 to the crosshead 20, so that reciprocation of the crosshead in the manner heretofore described correspondingly moves rod 110. Normally rigid on this rod 110, but detachably and adjustably secured in position through the clamping-bolt 116 is a bracket arm 118, of such a length and so positioned that, as clearly shown in Figs. 2 and 3, it extends under crosshead 96 and the lower end of plunger 94. Bracket arm 118 carries a vertical rod 120 detachably securable in selected position 85 by any suitable means, as the set screw 122. Connecting to the lower end of this rod 120, for instance through the agency of a ring 124 thereon, are two retractile springs 126 whose upper ends are secured to the crosshead 96, heretofore referred to, by any suitable means, as for instance the screws 128. These springs serve the function of normally urging the rod 110 and consequently the crosshead 20, working tool 38 and attached parts upward, thus holding the working-tool above and clear of mold 88 under normal conditions when the operator is not manipulating the shaft 26 through either one of the hand-levers. By loosening the screw 122 100 and moving the rod 120 as desired, the tension of the springs 126 for this purpose may be varied at the will of the operator.

General operation.

Starting with the parts in the position of Figs. 1, 2 and 3: The operator places some of the material to be tamped into the finished core in and on top of the mold 88. He takes hold of lever 28 and rotates shaft 26 in a counterclockwise direction, thus bringing tool 38 and attached parts down into the mold to tamp the material. He may rock the shaft backward and forward for this purpose several times. He then places more material in the mold and repeats this operation until the mold is tamped full of core material. In the final movement under this operation the core is formed with a slight indentation in its top due to the 120 projecting end 44^a of tool 44 being in the position shown in Fig. 3, slightly below the normal end of tamping tool 38. He then brushes away the surplus material from the top of the mold; then takes hold of lever 66 125 and swings it from the position of Fig. 1 to that of Fig. 7, the tool mechanism thereby assuming the position shown in Fig. 4. He then takes a previously prepared carbon pencil and places it in the bottom end of tool 130

38, as shown in Fig. 4. He then takes hold of hand-lever 28 and again rocks shaft 26 in a counter-clockwise direction thus depressing tool 38 toward the core in the mold 5 88 until it is stopped at the top of the core by the engagement of rod 78 with stop 82, heretofore described. That is to say, it reaches the position of Fig. 5, wherein the carbon pencil is inserted in final position 10 within the core.

The operator now either pushes handle 28 or pulls handle 30 which is provided for the purpose, to rotate shaft 26 in a clockwise direction and carries this movement on until 15 rack 22 has moved upward just as far as it can be made to go under the construction of gear 24. This movement is sufficient to raise rod 110 and consequently bracket 118 to such a height that plunger 94 is moved upward 20 a sufficient distance to eject the finished product in the mold 88. This movement also brings end 66^a of lever 66 into engagement with stop 74 so that the upward movement of the crosshead 20 to its extreme upper position (shown in dotted lines in Fig. 1) 25 rotates the lever 66 and consequently disk 56 and attached parts from the position of Fig. 7 back to the normal position of Figs. 1, 2 and 3, wherein the machine is ready to repeat the operation.

It is to be noted that the device heretofore described has several distinct advantages over those of the prior art. Among them are the facts that the crosshead 20 and attached parts move in a fixed guide and the essential tool 38 which is present in all the operations moves fixedly in unison therewith, thus insuring positive, accurate centering and operation of the tool every time it 40 is moved; to change the tool 38 from a purely tamping tool it is only necessary to move lever 66, which can be done easily and conveniently, and which does not in any way disturb the accurate operation of the main 45 tool 38; the switching of the machine from the tamping operation to the ejecting operation only requires the reversal of direction of movement of shaft 26. This can be accomplished by the operator without loosening his hold upon the handle 28 or 30, as the case may be. Due to the presence of the springs 126, all the parts of the machine are practically counterbalanced so that very little effort is required in its operation.

55 Having thus described my invention, what I claim as new and desire to secure by Letters Patent, is:—

1. In mechanism of the class described, a driven member, a tool rigid with said driven member, and mechanism carried by the driven member for changing the working characteristic of said tool without moving said tool on said driven member.

2. In mechanism of the class described, 60 a reciprocating member, a tool carried by

and rigid on the reciprocating member provided with a certain formed working face, and means carried by the reciprocating member adapted to be moved to vary the character of the working face of the tool 70 without changing the relationship of the tool to the reciprocating member.

3. In mechanism of the class described, a moving member, a tool rigid with and carried by the moving member, a plunger inside the tool, and means carried by the moving member manipulatable by the operator to change the position of said plunger with reference to the tool.

4. In mechanism of the class described, 80 a moving member, a tool carried by the moving member, a member reciprocatable with reference to the tool, and means carried by the moving member for selectively varying the position of the reciprocatable 85 member with reference to the tool.

5. In mechanism of the class described, a moving member, a tool carried by the moving member, a member adjustable with reference to the tool, means carried by the moving member for adjusting the adjustable member, and mechanism controlling the amount of such adjustment, for the purposes set forth.

6. Mechanism of the class described, 90 combination with a suitable support, a member movable with reference thereto, a tool carried by the movable member, a member adjustable with reference to the tool, means carried by the movable member for adjusting the adjustable member, and means on the support engageable by the adjusting mechanism for restoring the parts to a predetermined position.

7. In mechanism of the class described, 100 a guiding mechanism, a crosshead movable in the guiding mechanism, a tool rigid with the crosshead, a member reciprocatable with reference to the tool, a rotatable member mounted in the crosshead, a connecting rod 110 between the rotating member and the reciprocating member on the tool, and means for selectively moving the rotatable member to adjust the reciprocatable member to the tool.

8. In mechanism of the class described, 115 a guiding mechanism, a crosshead movable in the guiding mechanism, a tool rigid with the crosshead, a member reciprocatable with reference to the tool, a rotatable member mounted in the crosshead, a connecting rod between the rotating member and the reciprocatable member on the tool, means for selectively moving the rotatable member to adjust the reciprocatable member to the 120 tool, and means on the guiding mechanism engageable by the rotating mechanism when the crosshead reaches a certain position to restore the parts to original position.

9. In mechanism of the class described, a 130

guiding mechanism, a crosshead movable in the guiding mechanism, a tool carried by the crosshead, means for reciprocating the crosshead variable distances, a member movable with reference to the tool, means on the crosshead for selectively moving said movable member with reference to the tool, and a stop mechanism operated by such movement of the member on the tool to 10 limit the movement of the crosshead.

10. In mechanism of the class described, a guiding mechanism, a crosshead movable in the guiding mechanism, a tool carried by the crosshead, means for reciprocating the 15 crosshead variable distances, a member movable with reference to the tool, means on the crosshead for selectively moving said movable member with reference to the tool, a stop mechanism operated by such movement of the member on the tool to 20 limit the movement of the crosshead, and mechanism on the guide adapted, when engaged, to restore the parts to original position.

11. In mechanism of the class described, 25 a guide device, a crosshead moving on the guide, a tool on the crosshead, a member movable with reference to the tool, a lever mechanism on the crosshead movable to move the member on the tool, a cam operated by the lever mechanism, a stop operated by said cam to control the movement of the crosshead after the member on the tool has 30 been moved, and means engaged by the lever mechanism, one position of the crosshead, to 35 restore the parts to original position.

12. In mechanism of the class described, the combination with a suitable frame, a reciprocatable tamping mechanism, a mold opposite the tamping mechanism, a reciprocatable mold ejecting mechanism, and a single operating mechanism movable in one direction to operate the tamping mechanism in the mold and movable in the opposite direction to operate the mold ejecting mechanism to eject the finished product from the 45 mold.

13. In mechanism of the class described, the combination with a suitable frame, a reciprocatable tamping mechanism, a mold 50 opposite the tamping mechanism, a reciprocatable mold ejecting mechanism, a single operating mechanism movable in one direction to operate the tamping mechanism in the mold and movable in the opposite direction to operate the mold ejecting mechanism to eject the finished product from the mold, and spring mechanism normally holding the parts in balanced position with the tamping mechanism clear of the mold.

60 14. In mechanism of the class described, in combination with a suitable frame, a stationary mold member, a reciprocatable plun-

ger in said mold normally forming the bottom of the mold, a tamping mechanism adapted for reciprocation toward and from 65 the end of the mold not occupied by the plunger, mechanism movable in a given direction adapted to move said plunger toward said mold, and means connecting said operating mechanism to the plunger so constructed that it is inoperative while said tamping operation is taking place, but when operated by said operating mechanism while moving in the opposite direction from that required for tamping, is adapted to cause 70 75 said plunger to eject the finished product from the mold.

15. In mechanism of the class described, a support, a tamping mechanism, a mold mechanism opposite to the tamping mechanism, a product ejecting mechanism in connection with the mold, and operating mechanism movable from normal position in two different directions; movement in one direction only tamping material in said mold 85 and movement in the opposite direction operating to eject the product from the mold.

16. In mechanism of the class described, a vertical frame, a shaft in said frame, a lever controlling said shaft, a rack and pinion mechanism operated by said shaft, a cross head operated by said last mentioned mechanism, a tamping plunger operated by the crosshead, a mold adjacent to the tamping plunger, mechanical means for ejecting product from said mold, means connecting said mold ejecting mechanism to said rack and pinion mechanism operative during only one portion of the stroke of said lever, for 90 95 the purposes set forth.

17. In mechanism of the class described, a vertical frame, a shaft on said frame, a lever controlling said shaft, a rack and pinion mechanism operated by said shaft, a 100 crosshead operated by said last mentioned mechanism, a tamping plunger operated by the crosshead, a mold adjacent to the tamping plunger, mechanical means for ejecting product from said mold, means connecting said mold ejecting mechanism to said rack and pinion mechanism operative during only one portion of the stroke of said lever, and spring mechanism sustaining and 105 balancing the parts in normal position with the tamping tool clear of the mold, for the 110 115 purposes set forth.

In witness whereof, I have hereunto subscribed my name in the presence of two witnesses.

JOHN GRAVES.
